ATTORNEY

UNITED STATES PATENT OFFICE.

GERALD W. HART, OF WEST HARTFORD, CONNECTICUT.

DESIGN FOR A SWITCH CONTACT MEMBER.

SPECIFICATION forming part of Design No. 29,582, dated November 1, 1898.

Application filed September 6, 1898. Serial No. 690,338. Term of patent 14 years.

To all whom it may concern:

Be it known that I, GERALD W. HART, a citizen of the United States, residing at West Hartford, county of Hartford, State of Connecticut, have invented a certain new and original Design for a Switch Contact Member, of which the following is a full, clear, and exact description.

In the accompanying drawing the figure thereon is a plan or top view of my switch contact member.

The leading characteristics of my switch contact member are a main portion A, a curved portion B, projecting therefrom, the

outer end of said curved portion B merging ¹⁵ into another curved portion C, the curve of the latter being formed on substantially an arc of a circle.

What I claim is—

The design for a switch contact member ²⁰ herein shown and described.

Signed at Hartford, Connecticut, this 2d day of September, 1898.

GERALD W. HART.
